G. F. GILLETTE.
INTERNAL COMBUSTION ENGINE VALVE.
APPLICATION FILED MAR. 23, 1914.

1,132,084.

Patented Mar. 16, 1915.

UNITED STATES PATENT OFFICE.

GEORGE F. GILLETTE, OF DETROIT, MICHIGAN.

INTERNAL-COMBUSTION-ENGINE VALVE.

1,132,084.

Specification of Letters Patent.

Patented Mar. 16, 1915.

Application filed March 23, 1914. Serial No. 826,652.

To all whom it may concern:

Be it known that I, GEORGE F. GILLETTE, a citizen of the United States, residing at Detroit, in the county of Wayne, State of Michigan, have invented new and useful Improvements in Internal-Combustion-Engine Valves, of which the following is a specification.

This invention relates to an improved 10 valve mechanism for internal combustion engines and the like; and consists particularly in the provision of a simple and efficient revolving valve in the form of a sleeve or collar at the upper end of, and 15 surrounding, the cylinder in which the piston operates.

There are many details of novelty in my invention, and many corresponding advantages; and these details all depend more or 20 less closely upon the fundamental features of my valve, which may be briefly explained as follows:

I provide a short collar valve to fit either 25 around the cylinder into an enlarged portion at the upper end of the cylinder in which the piston reciprocates, this collar valve extending above the piston travel and being driven through a suitable mechanism 30 preferably at the top of the cylinder. An essential feature of the valve is its configuration as a collar and its placement at the upper end of the cylinder above the piston travel. I may either place the collar inside 35 or outside the cylinder head; that is, I may either place the collar directly adjacent the combustion chamber at the upper end of the cylinder, or I may place the collar outside the cylinder head. In either event the fundamental operation and effect is the same. I provide inlet and outlet ports 40 through the cylinder or through the cylinder head and through the collar. These ports may be what I term single line ports or may be what I term double line ports. 45 That is, the sleeve has two ports; and the arrangement may be such that one of these sleeve ports registers with one only of the cylinder ports, and the other sleeve port with the other cylinder port only, or each 50 sleeve port may register with both cylinder ports. In the last case, the ports are all arranged along a single circumferential line; in the first case the ports are arranged along two circumferential lines. These features 55 are all clearly explained in the follow-

ing specification and are shown in detail in the accompanying drawings, in which,

Figure 1 is a vertical section showing my invention embodying the double line ports, Fig. 2 is a section taken on line 2-2 of Fig. 60 1, Fig. 3 is a section similar to Fig. 1, showing a modification of the double line port arrangement, Fig. 4 is a section taken as indicated by line 4-4 of Fig. 3, Fig. 5 is a section similar to Fig. 1, showing the single 65 line port arrangement, Fig. 6 is a section taken on line 6-6 of Fig. 5, Fig. 7 is a section similar to that of Fig. 5 showing a modification of the single line arrangement, Fig. 8 is a section taken on line 8-8 of 70 Fig. 7.

In the drawings, the numeral 10 may designate a cylinder which may be of ordinary construction except as hereinafter described.

Referring particularly now to Figs. 1 and 2, it will be seen that the valve 13 is located outside a head 14, revolving around the head 14 and within an outer valve casing 15. The head 14 is preferably formed integrally with the cylinder 10 and has inlet 80 and exhaust ports 16 and 17, while the casing 15 surrounding the collar valve 13 has inlet and exhaust ports 18 and 19. The exhaust ports are located on a line above the 85 inlet ports, so that an exhaust port 20 through the collar valve 13 will register with the exhaust ports 17 and 19 only, while the inlet port 21 through the collar valve 90 will register with the inlet ports 16 and 18 only. The ports 16 and 17 are preferably directly opposite each other, so as to balance the opposing pressures on the parts of the collar 13 which are exposed through these ports. The exhaust ports are preferably 95 larger than the intake ports, although this is not necessarily the case, so that the exhaust will open during a longer period of valve travel than will the intake port. The two sleeve ports are preferably of the 100 same circumferential extent, and equal to the circumferential extent of the inlet ports 16 and 18. The ports are so placed that proper inlet and exhaust for an ordinary four-cycle operation will be had; or the port 105 arrangement may be such as to operate an engine on any other cycle principle, it being the purpose of this invention to provide a valve mechanism generally for internal combustion engines and the like. The valve 13 110

travels in the direction indicated. At its upper part it has a flange 25 which extends over the head 14 of the cylinder, and at the center of this flange there is a hollow driving sleeve 26 carrying a beveled gear 27 on its upper end. The beveled gears 27 of any number of cylinders may be driven from a common shaft 28 on top of the cylinders, and this shaft may be driven through the medium of a cross shaft 29 from the crank shaft 30 of the engine. The pistons 11 are connected by rods 31 with the crank shaft 30 in the usual manner. Through this mechanism, the pistons and valves are coöperated.

In Figs. 3 and 4 I have shown my collar valve 13^a arranged on the inside of the cylinder 10, in the upper enlargement 12 thereof above the travel of the piston 11. The valve in its construction is practically similar to the valve shown in Figs. 1 and 2, and its action with regard to the piston is the same as described; with the exception that the ports are arranged somewhat differently on the valve and cylinder. The inlet and exhaust ports 21^a and 20^a in the valve are arranged exactly opposite each other and are of equal size; so that the pressure upon the walls of the cylinder through these port openings may be oppositely equalized, and so that the resultant pressure upon the collar valve may be equalized and balanced. This arrangement of the valve ports necessitates an arrangement of the cylinder ports 16^a and 17^a somewhat different from the arrangements shown in Figs. 1 and 2. The cylinder inlet port 16^a is of the same size as the valve ports, while the exhaust port 17^a is larger and is arranged close to the inlet port. It will be seen that the arrangement is such that, just as the valve exhaust port 20^a leaves the cylinder exhaust port 17^a, the valve inlet port 21^a is about ready to register with the cylinder inlet port 16^a. In practice I provide an overlap of about two and one-half degrees; that is, I allow the exhaust port to travel two and one-half degrees beyond the closed position before the intake port is opened. I also proportion these ports so that the exhaust port opens before the end of the expansion stroke and before the beginning of the exhaust stroke proper, being open throughout one hundred twelve and one-half degrees of valve travel. The inlet ports also remain open through more than ninety degrees travel of the valve, remaining open through one hundred degrees travel. In other words, the cylinder and valve intake ports are each of fifty degrees circumferential extent.

My valve mechanism lends itself very readily to accurate arrangement of the ports and accurate opening and closing of the exhaust and intake. Once the ports are properly arranged, and the valve properly set and timed, it is practically impossible for

the valve to change in its relation to the piston and crank shaft. Once properly designed and set, my valve needs no further attention to keep it properly operating.

In Figs. 5 to 8 I have shown the forms of my valve in which all the ports are arranged along a single circumferential line.

In Figs. 5 and 6 I have shown the valve 13^b arranged around the outside of cylinder head 14^b and inside the valve casing 15^b. The valve itself has inlet and exhaust ports 21^b and 20^b, each of which is adapted to register with the ports 16^b and 17^b in the head 14^b and with the ports 18^b and 19^b through the casing 15^b. This valve is designed to travel at one-half the speed of travel of the valve of Figs. 1 and 3, making one revolution to every four revolutions of the engine crank shaft, so that a valve port passes a cylinder exhaust port or a cylinder inlet port every two revolutions of the crank shaft. Halving the speed of rotation necessitates reducing the port sizes by one-half; accordingly the valve ports are of twenty-five degrees extent as are also the inlet ports 16^b and 18^b while the exhaust ports 17^b and 19^b are larger, being one-half the circumferential extent of the exhaust ports 17 and 19 shown in Fig. 2. The action of this valve is substantially the same as in the forms of Figs. 1 to 4, with the exception that each valve port performs identical functions; that is, each moving valve port registers with both of the stationary inlet and outlet ports.

In Figs. 7 and 8 I have shown another form of valve with ports arranged in a single line, the valve 13^c being arranged on the inside of the cylinder within the enlargement 12 above the piston travel. The ports 20^c and 21^c in the valve and the cylinder ports 16^c and 17^c are arranged as in the form shown in Figs. 5 and 6.

The valve of the forms shown in Figs. 5 to 8 is driven at one-fourth the speed of the crank shaft 30.

It will be seen that there are certain fundamentals underlying the different forms of valves which I herein set forth. These fundamentals include the provision of a short collar valve at the upper end only of the cylinder, above the piston travel. The valve may be arranged either within or without the cylinder, and the valve ports may be either of the single line or the double line arrangement. The details of driving the valve may be varied without departure from my invention. Although the direct driving connection to the valve may be changed, I prefer to use a valve with an upper flange and with a hollow driving sleeve above, making the valve in effect an inverted cup, the flange of which contains the valve ports. The extent of all the ports may be varied to suit requirements, to obtain longer or shorter openings, etc. I place the spark plug 45 centrally in

the cylinder head and in the valve. In the forms of Figs. 1 and 5 the spark plug 45 is placed directly in the head 14 within the hollow driving sleeve 26; in the forms of 5 Figs. 3 and 7, I place the spark plug 45^a or 45^c directly in the head of the valve within the hollow driving sleeve 26. This placement of the spark plug makes for efficient ignition, as the incoming gases pass directly 10 over or near the ignition points of the plug case 115.

A point to which I particularly draw attention is the formation of the valve with its flange forming in effect a floating head 15 for the cylinder; this is particularly shown in the views where the valve is placed in an enlargement of the upper end of the cylinder.

I claim—

20 1. In an engine, a cylinder and piston traveling therein, a cup-shaped valve seated in the end of the cylinder beyond the piston

travel therein, said valve having a head forming the end of the cylinder and a flange engaging the side walls of the cylinder, the 25 cylinder and flange having registering ports.

2. In an engine, a cylinder and a piston traveling therein, a cup-shaped valve seated in the end of the cylinder beyond the piston travel therein, said valve having a head 30 forming the end of the cylinder and a flange engaging the side walls of the cylinder, the whole interior of the cup-shaped valve being directly exposed to pressure within the cylinder, the cylinder and valve flange having 35 ports adapted to register during rotation of the valve.

In witness that I claim the foregoing I have hereunto subscribed my name this 21st day of March 1914.

GEORGE F. GILLETTE.
